COVERLET

Eugene R. Weisbender, Manhattan, Kans.

Application March 7, 1938, Serial No. 194,320

4 Claims. (Cl. 5—334)

(Granted under the act of March 3, 1883, as
amended April 30, 1928; 370 O. G. 757)

The invention described herein may be manufactured and used by or for the Government of the United States for governmental purposes only without the payment to me of any royalty thereon, in accordance with the provisions of the act of April 30, 1928, Ch. 460, 45 Stat. L. 467.

This invention relates to improvements in bed clothing and more particularly to coverlets such as blankets, covers, quilts, robes, and the like, adapted for use immediately over a reposer's body.

Broadly, the improvement resides in means attached to, or formed in, coverlets to prevent the exposure of the reposer's shoulders, sides, or back, to cold air or drafts when the coverlet becomes taut or suspended over the body. More particularly, the invention comprises a coverlet having spaced, substantially parallel flaps, tucks or folds formed therein or attached thereto, longitudinally thereof, and adapted to depend from the coverlet 20 to clothe a reposer's sides.

To eliminate upper sheets over the reposer and beneath the coverlets is common practice in hospital, penal, military and naval services and in the covering of infants and children, as well as the practice of many nonservice adults. The improved coverlet herein described, when used in the foregoing manner, eliminates the annoying discomfort, created in the use of conventional coverlets, of having one's sides or back exposed 30 to air tunnels which are invariably created along the sides of the body by reason of the inability to keep a coverlet tucked closely about the body. The elimination of such exposure is not only desirous in common practice but most generally a 35 necessity with respect to patients.

Other objects of my invention will be set forth in, and become apparent from, the following description, it being understood that the above general statements of the objects of my invention are 40 intended to generally explain the same without limiting it in any manner.

Articles of the class described having the characteristics of my invention and by which the invention may be practiced are intended to be illustrated by the accompanying drawing in which:

Figure 1 is a perspective view, partially in section, of a bed illustrating the application of the improved coverlet, while

Figure 2 illustrates the application of the coverlet when used in connection with cots or beds having a greater tendency to sag.

Figure 3 is a perspective view of an inverted section of a coverlet illustrating the application, formation and arrangement of the means

adapted to cover the sides of a reposer, as described and claimed.

Figures 4 to 7 and 9 are views of sections of coverlets illustrating modifications of the side covering means.

Figure 8 illustrates the convenient foldability of the coverlet.

Several embodiments of my invention are known to me and are embraced within the scope of the appended claims, but according to that by which the invention may be practiced, I provide flaps, tucks or folds 10 on, or in, a coverlet having a body-portion 11 of conventional size and material. The flaps, tucks or folds 10 are arranged in spaced relation longitudinally of the coverlet, i. e., 15 longitudinally as used, and are adapted to depend from the coverlet. Each flap, tuck or fold may be continuous throughout the length, or substantially the full length, of the coverlet, as shown particularly in Figures 4 to 8, or may be separated 20 at intervals as illustrated at 10' in Figure 9. Another modification is shown in an inverted position in Figure 3, wherein it will be seen that fixed flaps 10 are formed only along the ends of the coverlet which in turn form loose folds 10'' 25 in the intermediate body portion of the coverlet. The flaps are preferably spaced sufficiently to accommodate a body therebetween, and are of a depending width preferably comparable with that of the thickness, so to speak, of a person's 30 body.

In the use of cots as beds, such as those commonly called "Army cots" or hospital cots" and illustrated in Figure 2, the bed portion 12 inevitably sags hammock-like, particularly under the 35 weight of one's body, to such an extent that the upper-most portion of the body is below or substantially on a plane with the side frames 13 of the cot. In such instances, a coverlet over the body becomes suspended across the body to the 40 side frames of the cot and an air tunnel 14 is unavoidably created along the sides of the body and to which the body is exposed in the absence of my improvements. The same is true in the use of upright bedsteads, as illustrated in Figure 1, 45 where one's body acts as a suspension for a coverlet 11, suspending it tent fashion from the body to the side frames 13 of the bedstead, whereby the body is exposed to the air tunnels 14 created along the body by the suspended coverlet.

A similar exposure results when two persons occupy a bed, in which instance the coverlet invariably and unavoidably becomes suspended across the two bodies, thereby creating an air tunnel between the bodies as well as along the 55

outermost sides of the respective bodies. The conventional width of a coverlet is insufficient to permit each of the two parties to tuck the same closely to their sides and even if the coverlets are of sufficient width, the tucking invariably becomes pulled loose and the coverlet is either drawn taut or suspended across the bodies and from the bodies to the bed frames upon the first and slightest turn or movement of either party.

10 Another instance is the common practice of pinning or clamping coverlets sufficiently taut over infants to prevent their crawling from thereunder, raising up, or otherwise becoming uncovered. For such purposes it is usually necessary to pin the coverlet to the side frame of the crib or the mattress and as so pinned, air tunnels are necessarily created along the sides of the infant.

15

By my invention, a person's sides remain covered by the depending flaps, tucks or folds 10 of the coverlet even though air tunnels, as previously described, are created.

There are, within the scope of my invention, a number of manners in which the flaps, tucks or folds 10 may be formed, some of which are 25 illustrated in the drawing. As in Figures 6, 8 and 9, the flaps 10 may comprise separate pieces sewed to the body-portion 11 of the coverlet in such a manner as to provide depending portions; they may be formed by portions of the body-portion 11 of the coverlet, as shown in Figure 4, 30 by fixing folds or tucks therein and allowing the double portions to depend freely; they may be formed as illustrated in Figure 5, where the body-portion 11 consists of a series of strips sewed together in such a manner that a portion of each strip forms a portion of the coverlet body-portion with a depending edge portion forming the flap; they may be constructed as shown in Figure 7 35 with an added body-portion 11' attached to the web 11'' between the flaps 10; they may be formed as described hereinbefore with reference to Figure 3; or they may be formed in any other suitable manner, such for example as explained in connection with Figure 9.

40 The improved coverlet may be as conveniently and readily folded for storage as the conventional coverlet by merely raising the coverlet sufficiently for the flaps 10 to drop into parallelism with the body-portion 11 of the coverlet, as illustrated in Figure 8.

45 From the foregoing it will also be seen that one may roll or move from one compartment, formed by the flaps, to another and immediately be clothed, from the air tunnels, by the flaps of the compartment into which he moves.

Having described my invention, which I claim is:

1. A flexible body-contacting bed coverlet for human beings having longitudinal members disposed longitudinally from one end of said coverlet to the other between the side edges of the coverlet at intervals comparable with the width of a human body and depending freely from said coverlet a width comparable with the thickness of a human body.

5 10 15 20 25

2. In combination with a flexible body-contacting bed coverlet for human beings having a body portion, longitudinal coverlet members of a width and length comparable, respectively, with that of the width of a human body, and the length of said coverlet, said members each fixed along one edge thereof to said body portion longitudinally thereof between its side edges at intervals comparable with the width of a human body and depending edgewise from said body portion sufficiently to clothe the sides of a human body.

3. A bed coverlet adapted to lie in a substantially horizontal plane over and in contact with a human body, the improvement comprising a plurality of fixed longitudinally disposed tucks at 25 predetermined intervals across the head end of the coverlet, short flaps of a width substantially that of the thickness of a human body formed by said tucks depending freely from said coverlet and adapted to contactingly clothe the sides of 30 the neck of the human body, and loose folds formed by said tucks continuing longitudinally from said flaps and adapted to contactingly clothe the sides of a human body.

4. A bed coverlet for human beings adapted to 35 clothe the uppermost side of a human body, comprising a continuous fabric sheet, a plurality of substantially parallel pleats therein freely depending therefrom, in which the width of the depending pleats are substantially equal to the 40 thickness of a human body and the space between adjacent pleats is substantially equal to the width of a human body, and means fastening the fabric together at the base of said pleats whereby a coverlet is provided having body-covering portion adapted to lie in a substantially horizontal plane over and in contact with a human body with the pleats depending therefrom and adapted to lie in a substantially vertical plane extending from said body-covering portion to the bed upon which the body lies, and in which said pleats are adapted to lie along side of and in contact with a human body disposed beneath said body-covering portion.
